D11-160. OR D12,409 EX

DESIGN FOR STATUARY.

Design No. 12,409, dated August 9, 1881.

UNITED STATES PATENT OFFICE.

EDSON SANFORD, OF MERIDEN, CONNECTICUT.

DESIGN FOR STATUARY.

SPECIFICATION forming part of Design No. 12,409, dated August 9, 1881.

Application filed March 14, 1881. Term of patent 7 years.

To all whom it may concern:

Be it known that I, EDSON SANFORD, a citizen of the United States, residing at Meriden, in the county of New Haven and State of Connecticut, have invented and produced a new and original Design for Statuary, of which the following is a specification, reference being had to the accompanying photographs.

The object of my invention is for a new and original design for statuary, to be known as a representation of Saint John, the figure A standing on a base, B, the lamb C lying on the base B, the feet F' and F² of the statue placed at the side of the lamb C, the living waters of life, H, running under the right foot, F'. The statue of Saint John, A, is leaning on or bearing in his right hand, E, a staff, S, placed at the back of the right foot, F', and concealed from view. The heel of the left foot,

F², is slightly raised. The heels of the feet F' and F² come in close proximity to each other, with the lamb C lying on or around the base B, near the feet F' and F². The drapery L is thrown over the left shoulder, M, and is grasped and held by the left hand, D, at the waist. The head O is turned, looking to the right, with the right arm, P, straight out until it comes to the elbow R; then it turns upward at or about the angle of forty-five degrees. The staff or cross S is held and poised by the forefinger T. The three fingers V V V are closed or inclined inward toward the palm of the right hand.

I claim—

The statue of Saint John, as described.

EDSON SANFORD.
